CLAIM

The ornamental design for a lunch box, as shown and described.

DESCRIPTION

FIG. 1 is a first exploded perspective view of my new design;

FIG. 2 is a second exploded perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a third exploded perspective view thereof; and, FIG. 10 is a fourth exploded perspective view shown in closed state thereof.

The broken lines in the drawings depict portions of the lunch box that form no part of the claimed design.

1 Claim, 10 Drawing Sheets(56)
